UNITED STATES PATENT OFFICE

97,320

DESIGN FOR A TEXTILE FABRIC

Walter T. Young, New York, N. Y.

Application September 28, 1935, Serial No. 58,749

Term of patent 3½ years

To all whom it may concern:

Be it known that I, Walter T. Young, a citizen of the United States of America, residing in Manhattan, county of New York, and State of New York, have invented a new, original, and ornamental Design for a Textile Fabric, of which the following is a specification, reference being had to the accompanying drawing, forming part thereof, wherein the figure is a plan view of a piece of textile fabric showing my new design.

The characteristic feature of this design resides in a crinkled fabric consisting of a series of narrow ridges with irregular narrow sinuous black stripes woven between similar stripes of a contrasting color, resulting in areas of shimmered appearance.

I claim:

The ornamental design for a textile fabric, substantially as shown, and described.

WALTER T. YOUNG.
